MOUNTING ARRANGEMENT FOR A HIGH
INTENSITY LIGHT SOURCE

Hendrik de Jong, Jan Bergmans, and Willem Kortenray, Eindhoven, Netherlands, assignors to General Electric Company, a corporation of New York

Application February 5, 1938, Serial No. 189,006
In Germany February 13, 1937

4 Claims. (Cl. 240—11.4)

Our invention relates to a mounting arrangement for a high intensity light source, and more particularly to a liquid-cooled mounting therefor. The light projector, according to our invention, preferably comprises a liquid-cooled high-pressure vapor discharge tube, a reflector surrounding said tube, and a casing surrounding both said discharge tube and said reflector and provided with a suitable lens or window through which the rays of light emerge from the device.

As is well-known in the art, liquid-cooled high-pressure vapor discharge tubes have been successfully employed as sources of light and radiation which surpass by far incandescent lamps in specific luminous output and intrinsic brilliance while their dimensions have been advantageously reduced to such an extent that, particularly with searchlight and projector installations, the whole of the device comprising the tube, the reflector and the members for circulating the cooling medium have been reduced to much smaller dimensions than any heretofore known. With this concentrated and inherently advantageous construction of such devices there arose, however, great drawbacks as to the arrangement of the members for the supply and the discharge of the cooling liquid and of the electric current conductors of the discharge tubes.

According to the invention, the casing of the device contains a guide member for the cooling liquid which is formed in such manner that the members for the supply and the discharge of the cooling liquid are provided at the one end of the device and the current supply members of the tube at the other end thereof.

The novel device according to the invention is of very simple construction, the aperture provided in the reflector for the passage of radiations being closed by a transparent guide member which is arranged and formed in such manner that the cooling liquid flows along it on both sides but in opposite directions.

A suitable form of construction of the device is obtained when the supply member of the cooling liquid extends axially with respect to the tube and is surrounded by a chamber provided with an outlet tube and communicating with the cooling chamber.

The electric supply conductors of the discharge tube are preferably arranged in such manner that the one supply conductor is connected to the reflector so that the reflector and the casing form part of the circuit and preferably are grounded, whereas the other supply conductor

extends out of the device and is insulated from the casing.

It has been found to be particularly advantageous to construct the device in such manner that the tube, the guide member, the reflector and the electric supply conductors are united to form a unit which is arranged in the casing so as to be readily removable and replaceable therein. Also, the guide member is preferably arranged on the reflector in such manner as to be readily removable and replaceable.

Where the device according to the invention is to be used only for the emission of visible rays it is advantageous to form the guide member of a material transparent to visible rays but which will absorb the ultraviolet rays. But if, in such case, the radiation window or lens of the casing, instead of the aforesaid guide member, is made from a material transparent to light and retaining the ultraviolet rays, the ultraviolet rays emitted by the discharge tube will accordingly be absorbed solely by the window. These retained radiations are transformed into heat which may give rise to an excessive strain on the window, since the latter is cooled on one side only. However, by also making the guide member which closes the radiation aperture of the reflector from a material which will retain the ultraviolet radiation, conditions are materially more favorable, because this member is cooled by the cooling liquid on both sides so that reduction of the heat absorbed by the window is obtained.

The invention will be understood more fully by reference to the following description and to the accompanying drawing which represents, by way of example, one embodiment thereof.

In the drawing, Fig. 1 is a longitudinal sectional view of a device according to our invention while Figs. 2 and 3 are cross-sections of the device taken on the lines 2—2 and 3—3 respectively of Fig. 1.

The illustrated high-pressure mercury-vapor discharge tube 1 consists of a cylindrical quartz tube which is narrowed at the ends and contains two incandescent electrodes 2 and 3 which protrude during operation from the mercury by which they are surrounded. The said tube also contains a gas filling. The discharge tube 1 is mounted and arranged in the focal line of a likewise cylindrical reflector member consisting of a metal tube 5 which has secured to its inner wall a suitable reflecting coating or body 4 of suitable shape. A portion of the cylindrical wall of the metal tube 5 is cut away to provide a lon-

itudinally extending opening parallel to the axis of the discharge tube 1. This open side of the tube 5 is closed by a plate-shaped guide or partition member 6 transparent to radiations and mounted between the tube 5 and the reflector coating 4. The guide member 6 consists in the preferred embodiment of glass transparent to visible rays and absorbing ultraviolet rays, said glass having a composition similar to that of the glass utilized, for example, in incandescent lamp bulbs. The guide member 6 may be secured in place in the metal tube 5 by means of a wire secured to the tube 5, said wire not being shown in the drawing. At the end close to the electrode 2 the tube 5 is provided with a flange 8. At this end, the tube 5 contains an insulating body 9 slightly spaced from the end of the guide member 6 to thereby provide a slit 7. The insulating body 9 has secured to it that end of the discharge tube 1 which contains the electrode 2, and is provided furthermore with a contact member 10 which is electrically connected to the electrode 2. The current supply wire of the electrode 3 is conductively connected to the metal tube 5, as shown at 23 in Fig. 1.

The discharge tube 1, the reflector 4 and the guide member 6, together with the metal tube 5 provided with the contact member 10, form a removable and replaceable unit. This unit is arranged in the cylindrical bore 24, which acts as a cooling chamber, of a casing 11, said unit being secured to the latter by means of a cap nut 12. At a suitable point with respect to the opening in the metal tube 5 and to the light source 1 therein, the casing 11 is provided with a radiation window 13 which insures water-tight obturation and which consists of glass which may have the same composition as the glass plate serving as the guide member 6. At the end of the casing which is remote from the cap nut 12, the cooling chamber is closed by a wall 14 having a plurality of bores or openings 17 therethrough. The wall 14 is also provided with a central bore 25 having a screw thread, said bore serving to accommodate a cooling water supply member 15 provided with a flange 16. The several bores 17 are preferably arranged concentrically about the said central bore 25. Between the flange 16 and the wall 14, and co-axially surrounding the supply member 15, is a tube 18 which is provided with an outlet tube 22.

The casing 11 is provided with screws 19 which may serve for mounting the device and which may also be utilized for establishing connections to the ground.

The contact member 10 fits into a contact bus 26 of a cable connecting piece 20. The latter is provided with a fastening or clamping device 21 which grips the screw cap 12. The cable 20 leads to the terminal of a source of current which generally consists of a transformer whose other terminal is grounded.

The path of the cooling water through the device is indicated by the arrows in Fig. 1. As appears from the drawing, the cooling water enters through the supply member 15 axially of the electrode end 3 of the discharge tube 1 and, guided by the reflector 4, metal tube 5, and the guide member 6, it flows around the discharge tube. The cooling water then escapes through the slit 7 into the chamber 27 formed between the window 13 and the guide member 6, said chamber thus forming a liquid lens. The cooling water leaves this chamber 27 by flowing back along the guide member on the side remote from

the discharge tube, through the cooling chamber 24 of the casing 11 and through the bores 17 in the wall 14 until it reaches the interior of the tube 18, from which it leaves the device through the outlet tube 22. The use of the guide member 6 consequently renders it possible to provide the members for the supply and the discharge of the cooling liquid at the one end of the device so that, completely separated therefrom, the live electric supply conductors may be provided at the other end of the device. Full advantage is taken, therefore, of the minimized dimensions of the whole device without any complications occurring in the operating conditions.

The particular discharge tube 1 illustrated has an internal diameter of 2 mm. The tube is operated with a specific load of 400 watts per centimeter and has an intrinsic brilliance of about 33,000 international candles per square centimeter. The specific luminous output amounts to about 60 lumens per watt and the operating mercury vapor pressure to about 100 atmospheres.

The specific embodiment of our invention described above forms a source of radiation only for visible light. However, all the rays emitted by the discharge tube may, of course, be utilized in any desired manner. To that end, a material transparent to ultraviolet rays or a material having the desired transmitting capacity may be employed for the material of the guide member 6 and of the window 13.

What we claim as new and desire to secure by Letters Patent of the United States is:

1. A light projection device comprising a casing provided with a chamber having a window therein, a high intensity tubular lamp mounted in said chamber behind said window, a reflector member also mounted in said chamber behind said lamp, current-supply connections at one end of said device for supplying current to said lamp, inlet and outlet members at the other end of said device communicating with said chamber for circulating a cooling liquid therethrough, and guide means transparent to radiations from said lamp mounted in said chamber between said lamp and said window and arranged to control the flow of the cooling medium from said inlet member through said chamber past said lamp along one side of the guide means and back along the other side of the guide means to said outlet member.

2. A light projection device comprising a casing provided with a chamber having a window therein, a high intensity tubular lamp mounted in said chamber behind said window, a reflector member also mounted in said chamber and enclosing said lamp, said reflector member having a longitudinally extending aperture therein between said window and said lamp, current-supply connections for said lamp, inlet and outlet members communicating with said chamber for circulating a cooling liquid therethrough, and a guide member transparent to light rays mounted on said reflector member over the said aperture therein, said guide member being arranged to control the flow of the cooling liquid in said chamber so that it flows along both sides of said guide member but in opposite directions.

3. A light projection device comprising a casing provided with a chamber having a window therein, a high intensity tubular lamp mounted in said chamber behind said window and having current-supply conductors, a metallic reflector member also mounted in said chamber adjacent said lamp, one of said current-supply conductors

being connected to said reflector member and the other of said conductors being led through and insulated from one end of said casing, inlet and outlet members at the opposite end of said casing communicating with said chamber for circulating a cooling liquid therethrough, and a guide member mounted in said chamber and arranged to control the flow of the cooling liquid from said inlet member through said chamber past said lamp and back to said outlet member.

4. A light projection device comprising a casing provided with a chamber having a window therein, a high intensity tubular lamp mounted in said chamber behind said window, a reflector member also mounted in said chamber behind said lamp, current-supply connections at one end

of said device for supplying current to said lamp, inlet and outlet members at the other end of said device communicating with said chamber for circulating a cooling liquid therethrough, and guide means mounted in said chamber and arranged to control the flow of the cooling medium from said inlet member through said chamber past said lamp and back to said outlet member, said lamp, reflector member, guide member and current-supply connections being so constructed and arranged as to form a unitary structure whereby the same may be removed from and replaced in said casing as a unit.
